M. C. MILLER,
KNITTING MACHINE,
APPLICATION FILED MAR. 12, 1917.

1,262,967.

Patented Apr. 16, 1918.

UNITED STATES PATENT OFFICE.

MAX C. MILLER, OF CUMBERLAND HILL, RHODE ISLAND, ASSIGNOR TO JENCKES
KNITTING MACHINE COMPANY, OF PAWTUCKET, RHODE ISLAND, A CORPORA-
TION OF RHODE ISLAND.

KNITTING-MACHINE.

1,262,967.

Specification of Letters Patent. Patented Apr. 16, 1918.

Application filed March 12, 1917. Serial No. 154,191.

To all whom it may concern:

Be it known that I, MAX C. MILLER, a subject of the Emperor of Germany, residing at Cumberland Hill, in the county of 5 Cumberland and State of Rhode Island, have invented certain new and useful Improvements in Knitting-Machines; and I do hereby declare the following to be a full, clear, and exact description of the invention, such as will enable others skilled in the art to which it appertains to make and use the same.

The invention relates to knitting machines provided with independently operated 10 spring needles.

It is the primary object of the invention to provide a beard pressing mechanism which is simple and durable in construction, and which is adapted to operate efficiently and uniformly in high speed and fine gage machines. It is a further object of the invention to provide a mechanism of this character which will meet the practical requirements for properly pressing the beards of a circular spring needle machine constructed to knit seamless hosiery, and in which a varying portion of the needles are inactive during the reciprocatory knitting of the heel and toe pockets.

To these ends one feature of the invention contemplates the provision of a beard engaging presser in front of the needles, and a series of transversely movable needle pressers mounted back of the needles which are forced outward at the pressing point to bend or deflect the needles forward against the beard presser. The beard engaging presser is preferably, although not necessarily, in the form of a plate extending along or about the series of needles, since this form of presser may be so mounted that there is no relative travel between it and the needles along the series, and therefore no lateral pressure on the beards during the pressing. The needle pressers preferably consist of a series of pins mounted in the needle support back of the needles, and arranged to slide transversely or substantially at right angles to the needle series. The pins are arranged to engage the backs of the needles, and are preferably forced forward at the pressing point by a cam engaging the rear ends of the pins, and maintained in proper relation to the knitting 50 cams during the knitting. This construc-

tion is simple and rugged, does not require extreme accuracy in the arrangement of the needle pressers, and its efficient operation is not impaired or destroyed by the slight bending or distortion of the needles which 60 invariably occurs during their use, and which would prevent the proper operation of pressers mounted to register with and act on the beards of the needles.

In seamless stocking machines a portion 65 of the needles are usually raised so that they are not acted on by the knitting cams during reciprocatory knitting on the heel and toe, and needles are shifted from the active to the inactive series, and from the inactive 70 to the active series, as the knitting progresses, to narrow and then widen the fabric. Outward bending of the inactive needles by the pressing mechanism during the knitting of this part of the fabric is 75 liable to interfere with the proper feed of the yarns to the active needles. A further feature of the invention accordingly contemplates the provision in a machine in which the needles are forced outward to 80 bring their beards against a beard presser, of means for rendering the mechanism which forces the needles outward inactive upon the needles in the idle series. In combining this feature of the invention with 85 the feature outlined above, it is preferred to provide the needles which may be raised into the inactive series with recesses which will register with the needles pressers when the needles are in the inactive series. With 90 this construction the raising of a needle into the inactive series renders the corresponding needle presser inactive upon that needle, since the presser will move forward idly into the recess in the needle when advanced 95 by the presser cam.

The features of invention outlined above, as well as further features referred to in the claims, will be readily understood by those skilled in the art from an inspection 100 of the accompanying drawings and the following detailed description of the mechanism illustrated therein.

In the drawings, Figure 1 is a partial sectional elevation showing so much of a 105 knitting machine as is necessary to illustrate the application of the present invention thereto; Fig. 2 is a detailed sectional plan view on line 2, Fig. 1; Fig. 3 is a sectional view showing the relation of the 110

needles in the idle series to the needle pressing pins and cam; Fig. 4 is a plan view of the parts indicated in Fig. 1; and Fig. 5 is a detailed view showing a portion of the upper end of the needle supporting cylinder.

In the drawings the invention is shown as embodied in a rotary needle machine adapted for knitting seamless stockings or half hose. The needle cylinder is indicated 10 at 1, and is provided at its lower end with a gear 2 through which rotary and reciprocatory motion is imparted to the needle cylinder in knitting the various parts of the stocking. The needle cylinder is provided 15 with the usual vertical grooves 3 in which the spring needles 4 are mounted to reciprocate. The needles are secured to jacks 5 fitted within the grooves 3, and provided with butts 6 arranged to be acted upon by the knitting cams, one of which is indicated 20 at 7, and also to be acted upon by the cams for raising the long butt instep needles up into the inactive series, the pickers for effecting the narrowing and widening, and 25 the cam for returning the instep needles to the active series, all of which parts may be of any usual or well-known construction. The upper end of the needle cylinder carries a web holder ring 8 provided with radial 30 grooves for the web holders 9, which may be operated in the usual manner by a cam ring 10.

The mechanism for pressing or closing the beards of the spring needles, so that they 35 will enter the loops on the needles as the needles are drawn downward, preparatory to casting off these loops and drawing the new loops therethrough, comprises a beard pressing member arranged in front of the 40 needles, and needle pressers mounted in the needle supporting cylinder and forced forward at the pressing point to bend the needles outward and bring their beards against the beard pressing member. In the construction 45 shown the beard pressing member is in the form of a beard pressing ring 11 surrounding the needles, and mounted to turn with the needle cylinder so that there will be no lateral pressure on the beards of the 50 needles when they are forced against the ring. The beard pressing ring is provided with a depending flange surrounding a rib 12 on the web holder ring 8, and held thereon by a clamping bolt 13. The needle pressers consist of a series of pins 14 mounted 55 to move radially in the upper end of the needle cylinder and to engage the backs of the needles. These pins are preferably arranged in two staggered rows, as indicated 60 in Fig. 5, so that they collectively occupy the entire circumference of the cylinder. When thus arranged, the edges of the pins are either substantially in line or overlap, so that some part of the outer end of one or 65 more of the pins will register with each needle,

thus insuring the engagement of each needle by one or more of the pressing pins, even in the finest gage machine.

As shown in Fig. 5, the pins correspond in number to the needles, and are arranged in line with the needles. This is not essential, however, as the size of the pins may be increased, with a corresponding decrease in the number of pins, and each pin may be of sufficient size to engage two or more needles. 70 The needle pressing pins are forced outward at the pressing point by a cam 15, over which their rear ends ride during the travel of the needle cylinder. As shown, this cam is formed on the outer side of a tube 16 75 which extends down through the needle cylinder, and is provided at its lower end with a lug 17 arranged to engage one or the other of two stop plates 18 and 19, which are adjustably secured to a fixed disk 20. During 80 rotary knitting the needle pressing cam 15 is maintained in proper relation to the stitch cam 7 by the engagement of the lug 17 with the stop 18. During reciprocatory knitting the cam 15 is shifted to coöperate first with one stitch cam and then with the other by the frictional engagement of the pins 14 with the cams, the lug 17 shifting from one stop to the other in the same manner that the web holder cam shifts in this type of 85 machine.

In order that the needles which are in the inactive series during reciprocatory knitting shall not be pressed outward by the cam 15 and pins 14, and thus interfere with the 100 proper lead of the yarn to the first needles in the active series, the needles are provided with recesses 21 at points which register with the pins 14 when the needles are in the inactive series. The result is that the pins 105 which would normally act upon the inactive needles move forward idly into the recesses as these needles pass the pressing point.

While it is preferred to employ the specific construction and arrangement of parts 110 shown and described, particularly in embodying the invention in a rotary cylinder spring needle machine of the type illustrated, it will be understood that this construction and arrangement is not essential to 115 the broader features of the invention, and may be varied and modified as found desirable or best suited to the construction or type of machine in which the invention is to be embodied.

Having explained the nature and object of the invention, and specifically described one form of mechanism in which it may be embodied, what is claimed is:—

1. A knitting machine, having, in combination, a series of independently operated spring needles, a beard engaging presser in front of the series at the pressing point, transversely movable needle pressers back of the series of needles, and means for forcing 125

- the needle pressers forward at the pressing point.
2. A knitting machine, having, in combination, a series of independently operated spring needles, a beard engaging presser in front of the series at the pressing point, a series of reciprocating pressers arranged back of the needles, and a cam for advancing the pressers at the pressing point to bend the needles outward against the beard engaging presser.
3. A knitting machine, having, in combination, a needle cylinder, independently operated spring needles mounted in the cylinder, an outside beard engaging presser, radially movable needle pressers inside the needles, and means for advancing the pressers at the pressing point.
4. A knitting machine, having, in combination, a needle cylinder, independently operated spring needles mounted in the cylinder, a relatively stationary presser ring surrounding the needles, needle pressers mounted for radial movement in the cylinder back of the needles, and means for advancing the pressers at the pressing point.
5. A knitting machine, having, in combination, a rotary needle cylinder, independently operated spring needles mounted in the cylinder, an outside beard engaging presser, radially movable needle pressers inside the needles, and a relatively stationary cam at the pressing point for advancing the pressers.
6. A knitting machine, having, in combination, a needle support, a series of independently operated spring needles mounted in the support, a relatively stationary presser plate in front of the needles, needle pressers mounted to reciprocate in the support back of the needles, and means for advancing the needle pressers to press the beards of the needles against the presser plate at the pressing point.
7. A knitting machine, having, in combination, a needle support, a series of independently operated spring needles mounted in the support, a presser plate in front of the needles, a series of needle presser pins mounted in the support back of the needles, and a cam for advancing the pins at the pressing point.
8. A knitting machine, having, in combination, a needle cylinder, a series of independently operated spring needles mounted in the cylinder, a beard engaging presser in front of the needles at the pressing point, means active on the active needles at the pressing point to press them outward against the beard presser, and inactive on the needles when raised into the inactive series.
9. A knitting machine, having, in combination, a needle cylinder, a series of radially movable pressers mounted in the cylinder, a series of spring needles mounted in the cylinder for movement into or out of active relation to the knitting cams, and provided with recesses registering with the pressers when in inactive relation, a cam for advancing the pressers at the pressing point, and a beard engaging presser against which the beards are pressed by the advance of the needle pressers.
10. A knitting machine, having, in combination, a needle cylinder, a series of radially sliding needle pressing pins in the cylinder, a series of spring needles mounted in the cylinder, a cam for forcing the pins outward at the pressing point, and a beard presser against which the needles are forced by the pins.
11. A knitting machine, having, in combination, a needle cylinder, a series of radially sliding pressing pins in the cylinder, a series of spring needles mounted in the cylinder, a cam for forcing the pins outward at the pressing point, means for shifting the cam with relation to the knitting cams during reciprocatory knitting, and beard pressing means against which the needles are forced by the needle pressers.
12. A knitting machine, having, in combination, a needle cylinder, a series of radially sliding needle pressing pins in the cylinder, a series of spring needles mounted in the cylinder, a cam for forcing the pins outward at the pressing point, a tube within the cylinder carrying the cam, a lug on the lower end of the tube, and stops for positioning the tube and cam with relation to the stitch cams.
13. A knitting machine, having, in combination, a needle support, independently operated spring needles mounted in the support, a series of needle presser pins mounted in the support back of the needles and arranged to collectively occupy a space extending from one end of the series of needles to the other, means for forcing the pins outward at the pressing point, and a beard engaging presser against which the beards are pressed by the advance of the pins.
14. A knitting machine, having, in combination, a needle support, independently operated spring needles mounted in the support, a series of presser pins mounted in the support back of the needles and arranged in staggered rows with the edges of the pins substantially in line or overlapping, a cam for advancing the pins at the presser point, and a beard engaging presser against which the needles are forced by the advance of the pins.
15. A knitting machine, having, in combination, a needle cylinder, independently operated needles mounted in the cylinder, radially movable needle pressers inside the needles, and a cam for advancing the pressers to outwardly bend the needles at a predetermined point.

- 4
16. A knitting machine, having, in combination, a needle cylinder, a series of independently operated needles mounted in the cylinder, a series of radially sliding needle pressing pins mounted in the cylinder, and a cam for advancing the pins to bend the needles outward at a predetermined point.
17. A knitting machine, having, in combination, a needle cylinder, a series of radially sliding needle pressing pins in the cylinder, 10 a series of needles mounted in the cylinder, a cam for forcing the pins outward, a tube within the cylinder carrying the cam, a lug on the lower end of the tube, and stops for positioning the tube and cam with relation 15 to the stitch cams.

MAX. C. MILLER.
